UNITED STATES PATENT OFFICE.

ERNEST H. BENNETT, OF EAST ORANGE, NEW JERSEY.

DESIGN FOR A RUG.

SPECIFICATION forming part of Design No. 35,086, dated September 10, 1901.

Application filed August 17, 1901. Serial No. 72,451. Term of patent 3½ years.

To all whom it may concern:

Be it known that I, ERNEST H. BENNETT, a citizen of the United States, residing at East Orange, State of New Jersey, have invented 5 and produced a certain new and original Design for a Rug, of which the following is a full, clear, and exact description, reference being had to the accompanying drawing, forming a part of this specification.

My design is applicable to and intended for the surface ornamentation of woven rugs. In its essentials it consists, as shown in the drawing, of a border composed of four similar leaf figures A, each pair united centrally by a scroll figure b, these with corner-scrolls forming the border. The field center is occupied by an oval bunch B, of flowers and leaves. 15

I claim—

The design for a rug substantially as shown and described. 20

In testimony whereof I have hereunto affixed my signature this 14th day of August, A. D. 1901.

ERNEST H. BENNETT.
